UNITED STATES PATENT OFFICE.

MICHAEL A. FLYNN, OF AKRON, OHIO.

TUBE VULCANIZER.

Application filed November 3, 1925. Serial No. 62,511.

This invention relates to vulcanizers for inner tubes of pneumatic tires, being designed and intended to improve upon former constructions for this purpose, and particularly intended and adapted for the vulcanization of inner tubes while in circular condition and while internally expanded by air or steam.

The invention is shown and described for use with chambered or steam jacketed molds and comprises a light metal shell or holder in which the tube is positioned prior to vulcanization, the shell and tube being placed within a mold for the required time to properly vulcanize the tube. The tube and shell are then removed and a fresh shell and tube put in place thereof. In this manner a mold may be used economically and efficiently.

20 The shell is shaped so that it readily and accurately seats in position, a portion of the tube only being enclosed therein. The remainder of the tube contacts directly with a side wall of a mold section, which closes in 25 the side of the removable shell.

The advantages of the apparatus will be apparent to those skilled in the art, it being evident that with a number of the shells or holders, it is possible to accurately position 30 and adjust a tube within a shell which is at room temperature, and the shell and tube can be placed within a hot mold, thereby obtaining a greater productive capacity for the tube mold. In addition, the tube cannot 35 maturely contact the hot mold as is the case when the tube is inserted directly into the mold.

Additional objects of the invention are to provide a form of shell which will be strong 40 and easily handled. Other objects and advantages will be obtained as will be evident to those skilled in the art to which this invention appertains and as will be pointed out in the claims, it being understood that changes and modifications may be made 45 within the scope of the invention and it is not necessarily limited to exact conformity with the details.

In the drawings:

50 Figure 1 is a view partly in elevation and partly in section showing a complete mold unit;

Figure 2 is a cross-section on the line 2—2 of Figure 1; and

55 Figure 3 is a detail of the construction at the valve stem opening.

The main mold comprises two sections 1 and 2 which are divided along a plane through the center of the tube so that the mold can be opened for the removal and insertion of tubes and shells therein. The mold sections are shown as chambered for the circulation of a heating medium, preferably steam, although other devices may be used for heating the mold to proper curing 60 temperature. Any suitable clamping mechanism (not shown) may be utilized for holding the mold sections together.

The removable shell is shown at 3 and is preferably made of any suitable material, 70 aluminum being preferred for this purpose on account of its light weight and the ease with which it may be handled. As shown the shell is constructed so that it encloses about three-quarters of the tube, being 75 opened at one side to permit the insertion and removal of the inner tube which is indicated at 4. The shell is circular throughout its entire extent and its cross-section is substantially of the form of a hexagon having 80 four sides complete and a portion of a fifth side at the base or inner circumference of the tube. Three sides of the shell are received with correspondingly shaped walls on the section 1, while the fourth and fifth sides 85 thereof are received within recesses 5 and 6 on the inner wall of the section 2. The remainder of the tube enclosure is formed by the inner wall 8 of the mold section 2. In this way the mold parts along lines spaced apart 90 upon one side of the tube and objectionable rinds or flashes at the thread and inner circumference of the tube are avoided.

At the point where the valve stem passes through the shell, it is recessed, as shown 95 at 10, so that the valve stem can be passed into position. The recess is arranged to be closed by a small piece of metal 11 which is pinned or otherwise secured upon the mold section 2 in position to fit within the recess 100 when the mold is closed. The mold section is cut away, as at 12, so as to permit the molding of tubes with bent valve stems, as shown in Figure 2. A circular recess 14 is formed in the face of the ring 3 and the 105 filler piece 11 to receive a circular washer 15 which is used to obtain the compression of the tube about the base of the valve stem.

In the operation of the device, a number of shells are provided for each mold and the 110 tubes are placed within the shells while upon a table or conveyor, the shell resting for

this purpose upon the surface α . The tube is now partially inflated and accurately seated within the shell, in which it remains until the mold is ready to receive it. When the 5 mold is opened and the vulcanized tube with its shell is removed, a shell with an unvulcanized tube is dropped in its place and the mold is closed. Air or other fluid under pressure is admitted to the interior of the 10 tube through the valve stem and the tube will be vulcanized as is understood by those skilled in the art. The form of the shell may be varied, but the substantial hexagonal cross-section is preferred, as it affords a very 15 strong construction and seats readily within the mold cavity.

What is claimed is:

1. An apparatus for curing inner tubes under internal pressure, comprising two 20 chambered mold sections, and a removable circular shell located between said sections, said shell being substantially hexagonal in cross-section with one side and a portion of a second side removed, three sides of the 25 shell being seated within one mold section and the remainder of the shell being seated within the other mold section, the last named section having a protruding rib adapted to complete the tube cavity.
2. An apparatus for curing tubes under internal pressure, comprising two chambered mold sections and a circular removable shell having an opening about one side thereof through which the tube may be inserted, the 30 shell being adapted to lie within one mold section, the other mold section having a projecting rib adapted to fit within said opening to complete the mold cavity.
3. In an apparatus for the uses and pur- 35 poses set forth, a sectional mold, and a removable shell therein for receiving an inner tube, said shell being open at one side to permit the insertion of a tube therein, one of said mold sections having a projecting por- 40 tion adapted to fit within said opening to complete the tube molding cavity.
4. In an apparatus for the uses and pur- 45 poses set forth, a sectional mold, and a removable shell therein for receiving an inner

tube, said shell being open at one side for approximately one-quarter of the cross-section to permit the insertion of a tube therein, one of said mold sections having a projecting portion adapted to fit within said opening to complete the tube molding cavity. 55

5. In an apparatus for the uses and purposes set forth, a sectional mold, and a removable shell for receiving an inner tube and adapted to lie within one section, said shell being open at one side but provided 60 with a portion about its inner circumference which projects above the innermost line about the tube, said projecting portion being recessed for the reception of a valve stem. 65

6. In an apparatus for the uses and purposes set forth, a sectional mold, and a removable shell for receiving an inner tube and adapted to lie within one section, said shell being open along one side but provided 70 with portions which project above and below its inner and outer circumferences, respectively, the other section of the mold having a projecting portion adapted to close said opening and complete the tube molding 75 cavity.

7. In an apparatus for the uses and purposes set forth, a sectional mold, and a removable shell for receiving an inner tube and adapted to lie within one section, said shell being open at one side but provided 80 with an outwardly projecting portion about its inner circumference, said projecting portion being notched for the admission of a valve stem, and the other section having a 85 projecting rib adapted to close the opening within the shell and a filler piece to close said notch when the sections are brought together.

8. In an apparatus for vulcanizing inner tubes, a sectional mold, and a removable circular shell of substantially hexagonal cross-section, three sides thereof lying within one of said mold sections and a fourth side and portion of a fifth side lying within the other mold section, and a closure adapted to complete the tube cavity. 90
